United States Patent Office

Des. 216,150
Patented Nov. 25, 1969

216,150

RECREATIONAL VEHICLE LIGHT

Humphrey A. Lee, Pasadena, Calif., assignor to Coronado Manufacturing Company, Long Beach, Calif., a corporation of Delaware

Filed Aug. 16, 1968, Ser. No. 13,163

Term of patent 14 years

Int. Cl. D12—99

U.S. Cl. D48—32

FIG. 1 is a front perspective view of a recreational vehicle light showing my design;

FIG. 2 is a rear perspective view of the light;

FIG. 3 is a side elevational view of the light; and

FIG. 4 is a top plan view of the light illustrated in FIGURES 1 through 3 on a reduced scale.

I claim:

The ornamental design for a recreational vehicle light, substantially as shown.
